Primary Examiner — Kevin Rudzinski*(74) Attorney, Agent, or Firm* — Fitch Even Tabin & Flannery LLP**(57) CLAIM**

I claim the ornamental design for a curved light fixture, as shown and described.

DESCRIPTION

FIG. 1 is a bottom perspective view of my new design comprising a curved light fixture;

FIG. 2 is a rear perspective view of the curved light fixture of FIG. 1;

FIG. 3 is a front view of the curved light fixture of FIG. 1;

FIG. 4 is a rear view of the curved light fixture of FIG. 1;

FIG. 5 is a left side view of the curved light fixture of FIG. 1;

FIG. 6 is a right side view of the curved light fixture of FIG. 1;

FIG. 7 is a top view of the curved light fixture of FIG. 1; and,

FIG. 8 is a bottom view of the curved light fixture of FIG. 1.

The broken lines shown in the drawings illustrate portions of the light fixture that form no part of the claimed design.
